UNITED STATES PATENT OFFICE.

JOSEPH SEHOLM AND ERIC W. MELLIN, OF BLOOMFIELD, NEW JERSEY.

BRUSH.

1,182,222.

Specification of Letters Patent.

Patented May 9, 1916.

Application filed June 8, 1915. Serial No. 32,800.

To all whom it may concern:

Be it known that we, JOSEPH SEHOLM, a citizen of the United States, and ERIC W. MELLIN, a subject of the King of Sweden, 5 and residents of Bloomfield, county of Essex, and State of New Jersey, have invented certain new and useful Improvements in Brushes, of which the following is a specification.

10 This invention relates to a device for applying pasty substances and for polishing surfaces, being particularly adapted for use in combination with blacking, such as shoe blacking, stove blacking, and the like, and 15 while it is not limited to pasty materials and can be utilized for applying liquid material, it will be described in this specification as a device for applying pasty substances.

The invention provides a compact article 20 in which a daubing or applying element and a polishing element are fastened to a back, the elements being spaced apart, the space between them being utilized for holding a receptacle, such as a blacking box, against 25 the back, the back thus acting as a closure for the receptacle, the receptacle being held by a supporting means which is disposed so that the box is held in the above described position and can also be swung to a position 30 in front of one of the brushing elements, such as the dauber, so that material can be applied to the dauber from the contents of the box and then the box can be swung back out of position out of the way between the 35 brushing elements. The device as described in this specification is described as having brushing elements, although it will be understood that while a brush made of bristles is preferred, polishing devices made of felt 40 or similar soft material can also be employed.

The invention provides a brush of this kind in which the receptacle is yieldingly held in its normal position between the 45 brushing elements, but can be removed when desired and swung to its position in front of the dauber, the snap or holding device thus acting to normally hold the receptacle in a position out of the way and does not 50 necessitate being handled as a separate element, since when it is in its normal position it is embodied as part of the device.

The invention is illustrated in the accompanying drawing in which one embodiment 55 of our invention is shown, it being under-

stood that different shapes of various parts can be employed and their relations can be changed to an extent without departing from the scope of the invention.

In said drawing, Figure 1 is a top view 60 broken away in places to more clearly illustrate the invention, and Fig. 2 is a side view of the brush shown in Fig. 1, the central part being broken away to make the invention more clear.

The brush comprises a back which can be of various forms, but in the form shown it consists of a front part 10, a rear part 11 and a connecting plate 12, the connecting plate being fastened to the parts 10 and 11 of the back by screws 13 and 14 respectively, so that a substantially stiff structure is provided. A suitable handle can be placed on the brush, in the form shown this handle 70 consisting of an arch-shaped piece 15 which is fastened at its ends, by means of the screws 16, to the front and rear portions of the back, thus tending to assist in stiffening the device, although this handle is not essential and can, if desired, be made in other forms. Fastened to the back are separated 75 brushing elements, the brush illustrated comprising a brushing element 17 which forms the dauber and an element 18 which can be used for polishing purposes. For clearness 80 in description the device will be described as one used as a stove polishing brush, this being done merely for convenience, and it will be borne in mind that the brush can be used for any purpose to which it can be applied.

The blacking is usually supplied in boxes, and we provide a support for a box of blacking, this support being mounted so that the box of blacking can be swung to a position 95 between the brushing elements or to a position in front of the dauber whereby some of the contents of the receptacle or box can be transferred to the dauber. The form of support shown in the drawing consists of 100 arms 19 which are pivoted in bearings 20, the bearings 20 being made of strips of material formed with loops 21 at their ends and being slipped underneath the front end of the plate 12 and held in place by means of 105 the screws 13. The arms 19 are provided with eyes 22 on their ends. The receptacle holder is made so that it can be mounted on these arms, in the form shown the receptacle holder consisting of a wire formed in a sub- 110

stantially U-shaped or semi-circular form, as at 23, the wire 23 being extended so as to project beyond a semi-circular shape to form the spring ends 24, these spring ends being formed by doubling the strand back upon itself, as at 25, and then passing in the shape of pins or fingers 26 out through the eyes 22, and being preferably formed on their outer ends into handles 27. The receptacle holder is thus swiveled in the arms and can be turned when the arms are swung downward.

To provide a closure to prevent evaporation of the contents of the box or receptacle 28, we prefer to place a gasket or washer 29 against the bottom face of the plate 12 so that the top edge of the box resting against the washer will form a tight closure and prevent spilling or evaporation of the blacking or other material in the box or receptacle 28. We prefer to yieldingly hold the box in its normal or inoperative position as shown in the drawing, and for such purpose we illustrate one form which comprises a spring 30, the spring 30 being preferably fastened into place beneath the forward end of the handle 15 and then perforated to also receive the screw 16. The free end of the spring 30 is provided with a nose 31 which extends down through the opening 32 in the plate 12. The arms 19 are connected by a strand 33 which is bent upward so that its raised central portion 34 springs underneath the snap or spring 31 and the receptacle holder is thus held in position between the brushing elements, as will be understood.

When the device is to be used the brush can be held in one hand and thus one of the handles 27, when two are provided, can be used to push down on the support and by giving it a slight jerk the receptacle is released from the position it is in against the back and can be swung downward, the swiveled connection permitting the box to be held substantially level or even, and in this position the box can be placed with its open end against the face of the dauber 17 and blacking or other materials deposited on the face of one of the brushing elements, such as the dauber, and then the box can be swung back to the position between the brushing elements.

The plate 12 is usually provided at its sides with the flanges 35 which extend down on each side of the brush and not only help stiffen the structure, but provide means for hiding the supporting means when it is in its normal position, thus shielding the parts from engagement with clothing or from being entangled with outside elements. The fingers or pins 26 of the receptacle holder enter into slots 36 in the side flanges 35 of the plate 12. The

plate is preferably widened out at its central portion, as will be clearly evident from Fig. 1, so as to provide the necessary housing for the arms 19 and to permit the arms 19 to be spread sufficiently so that they will 70 pass up on the sides of the dauber 17 to permit the dauber to be passed into the box or receptacle 28 for its full depth so that all the material can be used from the box.

The illustration shows the dauber inclined slightly to the polishing part of the brush, but it will be understood that these angles are not essential and that the brushes can be placed in the same plane or can be otherwise suitably disposed on the back.

Having thus described our invention, we claim:

1. A brush comprising a back, a brushing element on the back, a support comprising swinging arms pivoted to the back and being formed on their outer ends into eyes, a U-shaped receptacle holder having pins projecting through said eyes and being provided on the ends thereof with handles, and a snap for holding the support in a predetermined position.

2. A brush comprising a back having a brushing element projecting therefrom, a support comprising swinging arms and a receptacle holder, the swinging arms having eyes on their outer ends, the receptacle holder being made of wire bent into a substantially semi-circular form, the ends of the wire projecting through the eyes of the arms and being formed on their outer ends into handles, and means for pivoting the arms to the back so that a receptacle in the holder can be swung to a position against the back adjacent to said brushing element, or swung to a position opposite the face of said element.

3. A brush comprising a back having a brushing element projecting therefrom, a support comprising swinging arms and a receptacle holder, the swinging arms having eyes on their outer ends, the receptacle holder being made of wire bent into a substantially semi-circular form, the ends of the wire projecting through the eyes of the arms and being formed on their outer ends into handles, means for pivoting the arms to the back so that a receptacle in the holder can be swung to a position against the back adjacent to said brushing element, or 110 swung to a position opposite the face of said element, the swinging arms being provided with a nose, and a snap to engage said nose when the receptacle is swung to a position against the back whereby the receptacle is 115 yielded in such position.

4. A brush comprising a back, a dauber, separated bearings on the back, arms swinging in the bearings, said arms being connected by a bent strand and having their 120

ends formed into eyes, a substantially semi-circular receptacle holder with its ends passing through the eyes and being formed into handles, and a spring nose under 5 which the strand of the arms is sprung.

5. A brush comprising a back consisting of two parts having a connecting plate, the plate having an opening therein, a spring plate having a nose at its end projecting 10 through the opening in the connecting plate of the back, separated bearings on the back, a pair of arms swinging in the bearings and having a connecting strand with a

raised central portion to engage the nose, the ends of the arms being formed into 15 eyes, and a receptacle holder projecting slightly beyond the semi-circular shape and having its ends projecting through the eyes and being formed into handles beyond said eyes. 20

In testimony that we claim the foregoing, we have hereunto set our hands, this 5th day of June, 1915.

JOSEPH SEHOLM.
ERIC W. MELLIN.
